Des. 210,679
Patented Apr. 2, 1968

210,679

CLOCK CASING

Monte L. Levin, New York, N.Y., assignor to General
Time Corporation, Stamford, Conn., a corporation
of Delaware

Filed Sept. 6, 1967, Ser. No. 8,507

Term of patent 14 years

(Cl. D42—7)

FIG. 1

FIG.2

FIG.3

FIG.4

FIG. 6

FIG. 5

FIG. 1 is a front perspective view of a clock casing showing my new design;

FIG. 2 is a rear perspective view;

FIG. 3 is a top plan view;

FIG. 4 is a front elevational view;

FIG. 5 is a rear elevational view; and

FIG. 6 is a left side elevational view.

The broken line showings are for illustrative purposes only.

I claim:

The ornamental design for a clock casing, substantially as shown and described.
